United States Patent Office

Des. 231,669
Patented May 21, 1974

231,669

DISH RACK

Arthur A. Krause, Hollywood, Calif., assignor to K-Tel
International, Inc., Minneapolis, Minn.

Filed Aug. 17, 1972, Ser. No. 281,415

Term of patent 14 years

Int. Cl. D7—05

U.S. Cl. D7—188

FIG. 1

FIG. 2

FIG. 1 is a perspective view of a dish rack showing my new design in folded position;

FIG. 2 is a right, rear perspective view of the dish rack in open position;

FIG. 3 is a top plan view thereof;

FIG. 4 is a rear elevational view;

FIG. 5 is a right side elevational view;

FIG. 6 is a front elevational view;

FIG. 7 is a detail cross-section view taken on line 6-6 of FIG. 3; and

FIG. 8 is a bottom plan view.

I claim:

The ornamental design for a dish rack, as shown.
